CLAIM

The ornamental design for a manifold, as shown and
described.

DESCRIPTION

Cross-reference is made to U.S. Design patent application
Ser. No. 29/713,833, titled "Manifold," filed Nov. 19, 2019,
all of which is expressly incorporated herein by reference.
FIG. 1 is an upper perspective view of a manifold showing
our new design;

FIG. 2 is a front view of the design of FIG. 1;

FIG. 3 is a rear view of the design of FIG. 1;

FIG. 4 is a first side view of the design of FIG. 1;

FIG. 5 is a second side view of the design of FIG. 1;

FIG. 6 is a top view of the design of FIG. 1;

FIG. 7 is a bottom view of the design of FIG. 1; and,

FIG. 8 is a lower perspective view of the design of FIG. 1.
The broken lines shown in the drawings are included for the
purpose of illustrating the unclaimed boundary and
unclaimed portions of the manifold. The broken lines form
no part of the claimed design.

1 Claim, 8 Drawing Sheets
